Primary Examiner — Cynthia M. Chin(74) *Attorney, Agent, or Firm* — Tarter Krinsky & Drogin LLP(57) **CLAIM**

The ornamental design for a twister toy, as shown and described.

DESCRIPTION

FIG. 1 is a top perspective view of the twister toy showing our new design;

FIG. 2 is a bottom perspective view thereof;

FIG. 3 is a front view thereof;

FIG. 4 is a rear side view thereof;

FIG. 5 is a right side view thereof;

FIG. 6 is a left side view thereof;

FIG. 7 is a top view thereof; and,

FIG. 8 is a bottom view thereof.

The dash-dot broken lines in FIGS. 2 & 8 represent the bounds of the claim and all other broken lines represent portions of the article that form no part of the claimed design. None of the broken lines form a part of the claim.
